Charles Erickson and Erick Spellman,
New York, N. Y.

Substituted for abandoned application Serial No.
82,598, January 25, 1939. This application No-
vember 30, 1939, Serial No. 88,725

Term of patent 7 years

All whom it may concern:

Be it known that we, Charles Erickson and Erick Spellman, both citizens of the United States of America, residing at New York city, in the county of Bronx and State of New York, have invented a new, original, and ornamental Design for a Refrigerating Unit, for Freezing and Dispensing Frozen Custard, or the like, of which the following is a specification, reference being had to the accompanying drawing, forming part thereof. The present is a substitute application for former application No. D-82,598, filed January 25, 1939.

Figure 1 is a front perspective view of a refrigerating unit, for freezing and dispensing frozen custard or the like, showing our new design; and

Figure 2 is a rear perspective view of the same.
We claim:

The ornamental design for a refrigerating unit, for freezing and dispensing frozen custard or the like, as shown.

C. ERICKSON.
